CARDING MACHINE CLEANER

James E. McWilliam, North Oxford, Mass.

Application August 28, 1933, Serial No. 687,091

3 Claims. (Cl. 19—108)

This invention relates to a breaker or finisher card used in the textile industry.

The principal objects of the invention are to provide means for constantly and effectively cleaning the card, run by the power of the machine, so as to avoid the usual frequent stopping of the machine for the purpose of the hand-card cleaning of the main cylinder; to provide this means in such form that it will also constantly clean and polish the teeth of the main cylinder and keep them clean; to provide means for reducing the amount of dirt carried into the yarn and reducing the waste very materially, and to provide this feature without adding to the space taken by the card or crowding the workers.

Other objects and advantages of the invention will appear hereinafter.

Reference is to be had to the accompanying drawing, in which

Fig. 1 is an end view of a card showing the cylinder, workers and other rolls and showing a preferred embodiment of this invention applied thereto;

Fig. 2 is an enlarged end view of a part of the main cylinder and showing its cooperation with the new cleaner roll which is the subject of this invention;

Fig. 3 is a side view of this cleaner, and

Fig. 4 is a sectional view on enlarged scale on the line 4—4 of Fig. 3.

This invention is shown as applied to a well-known type of card. It has been the practice, on account of the conditions existing in carding of wool and other fibers, to stop machines of this kind three or four hours every day, take out the rolls, and clean the main cylinder by means of hand cards. This results in a large proportion of loss of the production of the machine and adds to the cost of the labor. It has also been necessary to grind the teeth of the card cylinder to sharpen and polish them. The hand cards add to that necessity by the fact that the men have to move the hand cards back and forth along the teeth of the cylinder and when they move them backwardly, they tend to dull the teeth and spoil their sharp edges which are necessary for effective and clean carding. Also a large amount of dirt is carried into the yarn and a large amount of waste is distributed around the room from the ordinary card.

By this invention the loss of about three hours per day is almost entirely eliminated because the card will run for several weeks without cleaning. Furthermore, the main cylinder is kept clean all the time instead of the dirt thereon gradually in-

creasing. The amount of fiber forced down among the teeth also is materially decreased, so that irregularity in product produced by the old method is practically eliminated. It has been found in practice that the waste is reduced by practically one-third. Furthermore, as this machine polishes, cleans and sharpens the teeth constantly during its rotation, these teeth are kept in a uniform clean sharp condition at all times and therefore the product is much more uniform for this reason in addition.

The invention is shown as applied to a well-known type of card comprising a main cylinder or swift 10, licker-in 11 to take the material from the lap roll and introduce it into the machine on the cylinder 10. The machine is shown as provided with the usual workers 13, each one provided with its stripper 14, which cooperates with the worker and the main cylinder 10 in the usual manner and for the usual purpose. The usual fancy 15 and the doffers 16 are shown, although this invention is not necessarily applied to this particular type of card.

It has been stated that the usual workers are employed but as a matter of fact one of them is omitted and in place of it is employed a cleaner roll 17 which is the main part of the subject of this invention. This cleaner 17 has no stripper connected with it. All these cylinders and rolls, with the exception of the cleaner, are provided with regular card clothing as usual, or with any other ordinary substitute therefor, usually having bent teeth as shown in Fig. 2. The cleaner 17, however, is provided with straight teeth 18 which are made of what is called "flat wire", which is wire of rectangular cross section. For instance, this wire may be 34 gauge circumferentially and 28 gauge transversely, or round wire with pressed points can be used. These wires are set into a foundation 19 in such a way that when wound on the roll they may be tangent to a circle inside the roll of smaller diameter than the roll and concentric therewith. This gives them a backward incline with respect to the direction of rotation of this roll as will appear. This foundation 19 is made in a continuous length of a width of perhaps an inch and three-quarters, the central inch of which is provided with the teeth 18, although these dimensions can be varied in accordance with the kind of fiber being worked upon, and the same is true of the size or gauge of the teeth and their inclination. It will be noted that no stripper is used in connection with this cleaner.

The strip of foundation is wound on the roll 17 53

in a helical manner as shown in Fig. 3 from one end to the other and the parts of the foundation extending out on both sides of the area, say an inch wide, covered by the teeth is used conveniently for tacking the foundation to the roll and the two ends are secured by nails or in fact in any desired way. The space between the two adjacent convolutions of teeth-covered areas is preferably twice the width of the projecting part 10 of the foundation, that is—three quarters of an inch in the illustration given above, so that the foundation abuts at its edges as shown in Fig. 4. However, this is not essential, as the idea is to get the convolutions of teeth separated from each 15 other and it does not have to be filled between these convolutions with the foundation unless that is more desirable.

The direction of rotation of the main cylinder is indicated by an arrow in Figs. 1 and 2 and the 20 various rolls, except the cleaner roll 17, rotate in the usual directions. This roll 17 is connected by pulleys and a belt 20, with the fancy roll 15 preferably, so that it rotates at a higher rate of circumferential speed than the circumferential 25 rate of travel of the surface of the main cylinder and its direction is indicated by the arrows also.

In operation, the workers, fancy, doffers, etc. 30 operate as usual. This cleaner rotates at a higher surface speed than the cylinder, with the teeth extending into the teeth of the cylinder from one-eighth to three-sixteenths of an inch, according to the character of the fiber, and brushes the teeth of the cylinder so as to clean and polish them in a forward direction, and also stirs the fiber up on the cylinder so that it will be in 35 position to be taken up by the workers. This keeps this cylinder uniformly clean so that it will work for a long period of time without any variation in this feature and without any variation in product.

It will be noticed that the helical band of 40 straight teeth carried by the roll 17 has a tendency to push the fiber along the cylinder slightly and this is a very important feature. If this roll 17 were covered with a continuous area of wires or card clothing, it would stir up the fiber 45 on the cylinder too greatly. If it were operated like a vibrator it would tend to bring the fibers on the cylinder into a series of ridges so-to-speak, arranged circumferentially, and interfere with the uniformity of the product.

This simple device has all the advantages mentioned above. A main card cylinder will run 50 for several weeks without any cleaning or any sharpening or polishing of the teeth and the condition of the card will be uniform during that time so that there is no material variation of the product from one part of a day to the other, or day to day.

The stopping of the card several hours every 60 day, which is universal now so far as I am aware, is entirely eliminated. The use of hand cards for cleaning during these periods takes place only once in a month or more, and the grinding of the cylinder and polishing of the teeth are reduced 65 in the same proportion.

I am aware of the fact that the fancy roll 15, ordinarily employed on this class of machines, has some of the characteristics of this cleaning

roll. The card clothing which is used thereon is continuous from end to end and it is impossible to adjust these fancy rolls near enough to the main cylinder so that the teeth sink so far into the teeth of the cylinder as has been mentioned herein. The fancy roll is for the purpose of raising the material up out of the wires of the main cylinder into which it has been forced by its velocity in passing the different workers and strippers. But on account of the failure to separate the areas of the wires, as by the helical method shown herein, the action has been imperfect and it has not been able to produce the result of this cleaner. I use the cleaner in co-operation with the fancy roll so as not to lose 15 the benefit of that as ordinarily employed. This shows the advantage of the helical arrangement and the spacing of the areas of the wires on the cleaner roll.

This invention can be applied to the first or 20 second breakers or the finisher card or any other carding machine or other machine having a corresponding purpose. The disadvantage of removing one of the workers is more than made up by the advantages above mentioned and the production of the machine is greater and cleaner 25 and more uniform than it has been without this invention.

Although I have illustrated and described only one form of the invention, I am aware of the 30 fact that modifications can be made therein by any person skilled in the art without departing from the scope of the invention as expressed in the claims. Therefore, I do not wish to be limited to all the details of construction herein shown 35 and described, but what I do claim is:—

1. In a carding machine, the combination with 40 a main cylinder having teeth on its surface, a fancy engaging the surface of the main cylinder, workers, a stripper for each worker, and a rotary cleaning roll between two adjacent workers having teeth extending backwardly with respect to its direction of rotation and projecting into the teeth of the main cylinder farther than the teeth of the fancy do.

2. In a carding machine, the combination with 45 an ordinary main cylinder having teeth on its surface, a series of workers around it, each one provided with a stripper, a fancy engaging the surface of the main cylinder, and a cleaning roll located between two of the workers out of contact with both and having teeth extending backwardly with respect to its direction of rotation and projecting into the teeth of the main cylinder farther than the teeth of the fancy do. 55 and means for rotating the cleaner at a higher surface speed than that of the main cylinder.

3. In a carding machine, the combination with 60 an ordinary main cylinder having teeth on its surface, a series of workers around it, each one provided with a stripper, and a cleaning roll located between two of the workers out of contact with all rolls except the main cylinder and having teeth extending backwardly with respect to its direction of rotation and projecting into the teeth of the main cylinder, and means for rotating the cleaner at a higher surface speed than that of the main cylinder.

JAMES E. McWILLIAM.
